COMBUSTION TESTING APPARATUS

Filed August 31, 1923

INVENTOR

Richard P Brown
BY
John R. Hubbell

ATTORNEY

UNITED STATES PATENT OFFICE.

RICHARD P. BROWN, OF PHILADELPHIA, PENNSYLVANIA, ASSIGNOR TO BROWN INSTRUMENT COMPANY, OF PHILADELPHIA, PENNSYLVANIA, A CORPORATION OF PENNSYLVANIA.

COMBUSTION-TESTING APPARATUS.

Application filed August 31, 1923. Serial No. 680,339.

In determining combustion conditions it is frequently desirable to determine both the temperature and the chemical analysis of the furnace heating gases at some point 5 in the furnace or in the stack connection thereto; and the general object of the present invention is to combine a thermometric device, which ordinarily is a thermo-couple, with provisions for withdrawing furnace 10 gases for analysis, in a simple, compact, durable and effective instrument adapted to be mounted in the wall of, and to extend into a furnace chamber, smoke stack, stack flue or the like, to measure the temperature 15 of the furnace gases, and to withdraw a sample portion of such gases for analysis.

The various features of novelty which characterize my invention are pointed out with particularity in the claims annexed to 20 and forming a part of this specification; for a better understanding of this invention however, its advantages and specific objects attained with its use, reference should be had to the accompanying drawings and descriptive matter in which I have illustrated 25 a preferred embodiment of my invention.

The one figure of the drawing is a sectional elevation of my novel instrument and a portion of the furnace or flue in which it 30 is installed.

In the form and use of my invention illustrated in the drawing, A represents the wall of a boiler housing, stack, stack flue, or the like provided with an opening A' through which my novel instrument is inserted so that the thermo-couple junction C of the instrument will be exposed to the temperature of the furnace gases at the inner side of the wall A, and a sample portion 35 of the flue gas may be withdrawn for analysis through the annular space e between the protective tube D of the thermo-couple device proper, and the surrounding tubular casing member E. The tubular 40 parts D and E are rigidly connected at their outer ends by means including a part F, shown as a pipe fitting having an opening F' at its inner side into which the outer end of the pipe D is threaded, and an opening F² at 45 its outer side into which is secured the terminal box G of the thermo-couple. As shown the box G is provided with a nipple G' which is externally threaded and is 50 screwed into a suitable bushing H. The

latter is externally threaded and is screwed 55 into the opening F². The nipple G' is internally threaded, and has screwed into it the threaded outer end of the tube D whereby the tube D is rigidly held in the proper co-axial relation with the tube E. The fitting part F is also provided with a lateral outlet F³ into which is screwed the end of the pipe I through which the gases withdrawn through the channel C and fitting part F are passed to the gas analyzing apparatus proper. Advantageously the member F is formed with a lateral opening F⁴, located at the opposite side of the fitting from the opening F³, and normally closed by a plug J which may be removed when necessary to facilitate the removal of soot or other furnace dust accumulating in the device. Advantageously a flange member K is threaded onto the outer end of the tube E to bear against the outer face of the furnace 75 wall at the margin of the opening A'. The thermo-couple conductors c extend from the thermo-couple junction C through the tube D into the junction box G in which they are secured to binding posts G', through 80 which they may be connected to a milli-volt meter or other suitable electrical measuring instrument.

My improved testing instrument is obviously simple, compact, and durable, and 85 is well adapted for its intended use. The tube D which forms the outer wall of the annular gas channel C through which the gas for analysis is withdrawn, may readily be made of a material and weight to insure 90 it against injury by contact with the furnace wall when the instrument is being inserted and removed in a furnace wall opening, and to avoid deterioration from the temperature and chemical action of the furnace gases to which its inner end is exposed. The outer tube D, in addition to forming the outer wall of the annular gas channel e, 95 forms a protective shield about the less robust thermo-couple tube, which substantially eliminates possibility of injury to the latter by contact with the wall of the opening A in inserting or removing the instrument. The tubes B and E may be made of any suitable dimensions. To measure the 100 temperature and sample the flue gases in the last pass of a boiler, or in the stack, or stack flue of a boiler furnace, the tube E should

ordinarily extend into the gas space six inches or so from the inner side of the wall A, and the thermo-couple junction C should be located six inches or so beyond the inner 5 end of the tube E to prevent the junction C from being cooled by radiation to the pipe E, or from being lagged by the latter.

With the type of construction illustrated, a device to suit any particular condition of 10 use, such as furnace wall thickness the points in the furnace chamber from which the gas for analysis is withdrawn and the gas temperature taken, and the general temperature range to be measured, may be quickly and 15 readily assembled from standard parts which may be kept in stock. The construction also permits of the ready replacement of injured or unsuitable parts.

The fact that with my instrument, the 20 furnace gas temperature is read and the furnace gas sample is withdrawn from points in close proximity to, and definitely positioned with respect to one another adds to the informative value of the observations in 25 many cases.

While in accordance with the provisions of the statutes I have illustrated and described the best embodiment of my invention now known to me it will be apparent 30 to those skilled in the art that formal changes may be made in the apparatus disclosed without departing from the spirit of my invention as set forth in the appended 35 claims.

Having now described my invention, what I claim as new, and desire to obtain by Letters Patent, is:

1. An instrument comprising an elongated body adapted to be inserted into a gas 40 space through an opening in the wall thereof and formed with a longitudinal channel receiving gas from said space adjacent the inner end of said body and having an outlet

adjacent the outer end of said body through which gas may be withdrawn for analysis, 45 and thermometric means mounted in said body and including temperature responsive means adjacent the inner end of the latter for measuring the temperature of said gas space. 50

2. An instrument comprising a thermo-couple with its protecting casing, and a member surrounding said casing for a portion of its length and formed with a gas channel, having an inlet adjacent the hot 55 junction of said couple.

3. An instrument comprising in combination, a thermo-couple with its protective casing and a tubular element secured to and surrounding said casing and having an open 60 end from which the hot junction end of the thermo-couple projects for a short distance, said tubular element being separated from said casing to provide a gas channel extending longitudinally of the casing, and means 65 providing an outlet from said channel for gas entering the latter at said open end of said member.

4. An instrument adapted to be placed in an opening in the wall of a gas space, and comprising a thermo-couple at its inner end, and a protective casing therefor, a chambered fitting part attached to the outer end of said casing, a tubular member attached to said fitting part and surrounding said casing 70 for a portion of its length and separated therefrom by an annular gas channel open to said space at its inner end opening into said chambered part at its outer end, and a gas take off conduit secured to said fitting 75 part.

Signed at Philadelphia in the county of Philadelphia and State of Pennsylvania this twenty-eighth day of August A. D. 1923.

RICHARD P. BROWN.
